UNITED STATES PATENT OFFICE.

WILLIAM H. KOEHLER, OF JACKSON, MISSOURI.

SHINGLING-HATCHET.

1,168,890.

Specification of Letters Patent. Patented Jan. 18, 1916.

Application filed December 2, 1914. Serial No. 875,139.

To all whom it may concern:

Be it known that I, WILLIAM H. KOEHLER, a citizen of the United States, residing at Jackson, in the county of Cape Girardeau, State of Missouri, have invented certain new and useful Improvements in Shingling-Hatchets; and I do hereby declare the following to be a full, clear, and exact description of the invention, such as will enable others skilled in the art to which it appertains to make and use the same.

This invention relates to improvements in hatchets and more particularly to a shingling hatchet having means embodied therein for gaging and cutting shingles during the operation of laying same.

An object of the invention resides in the provision of a hatchet of this character in which the gaging and cutting elements thereof are formed integral with the hatchet blade, these elements being arranged in such manner as to interfere in no way with the successful operation of the hatchet proper.

With the above and other objects of similar nature in view, the invention consists in the construction, combination and arrangement of parts set forth in and falling within the scope of the appended claims.

In the drawings:—Figure 1 is a perspective view of a hatchet constructed in accordance with the invention, and Fig. 2 is a sectional view taken on the line 2—2 of Fig. 1, and Fig. 3 is a fragmentary perspective view of the blade, showing the V-shaped groove and cutter in detail.

Referring now more particularly to the drawing, the hatchet comprises the blade 10, head 11, socket 12 and handle 13, all constructed in the preferred manner of tools of this nature. In forming the gage whereby shingles may be conveniently laid with a uniform degree of lap, the upper edge of the blade is cut away as at 14 to provide a ledge or shoulder 15, said shoulder facing the head of the hatchet and being located the required distance therefrom, to obtain the desired lap, such distance being determined in accordance with the practice in various localities of the country.

Formed on the side edge of the blade 10 opposite from the gage and extending longitudinally thereof from its cutting edge 16 to the nail opening 17 usually found in

tools of this nature, is a V-shaped groove 18, the walls of which at its outer end converge and merge into said cutting edge whereby a V-shaped cutter 19 is provided. This cutter 19 is adapted to be employed in lieu of a saw or other like means in cutting shingles either square or on the bevel and may further be used in place of a pencil for marking rough boards or timbers, preparatory to sawing same.

It will be observed that by forming the cutter 19 in the manner as above described, when sharpening the blade 10 an edge will also be placed on the cutter and a saving of time and labor necessary in performing the sharpening operation consequently effected. It will further be noted, that as the blade 10 is repeatedly sharpened, the cutter 19, by reason of the groove 18 extending rearwardly to the nail opening, will at all times be present and in its proper shape so long as the original bevel on the edge is maintained.

Having now described the tool, in operation of the device, the shoulder 15 is engaged with the butt of the shingles already laid, in which position the head 11 serves as a gage for laying the shingles for the next row above, this operation being repeated for successive rows.

When employing the tool as a cutter, the cutting edge 19 is drawn across the face of the shingle and the parts thereof thus readily severed in the desired manner.

What is claimed, is:—

1. In a shingling hatchet, the combination with its cutting edge, of a supplemental cutter forming a continuation thereof, said cutter being formed by grooving a side edge of the blade longitudinally from its outer end and sharpening the latter in the usual manner.

2. In a shingling hatchet, the combination with its cutting edge, of a supplemental cutter forming a continuation thereof, whereby the blade and cutter may be sharpened at the same operation.

In testimony whereof, I affix my signature, in the presence of two witnesses.

WILLIAM H. KOEHLER.
